S. M. LUCAS

RAILWAY SIGNALING

Original Filed April 18, 1922

INVENTOR:

S. M. Lucas,
by A. Z. Venable
His attorney

UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Original application filed April 18, 1922, Serial No. 555,339. Divided and this application filed January 5, 1925, Serial No. 617. Renewed February 11, 1927.

My invention relates to railway signaling systems and particularly to systems of the type comprising electron discharge devices. More particularly my invention relates to systems embodying such devices in which the flow of current is controlled magnetically.

The present application is a division of my copending application Serial No. 555,339, filed April 18, 1922, for "railway signaling and relays for use therein."

I will describe two forms of signaling systems embodying my invention and will then point out the novel features thereof in 15 claims.

In the accompanying drawing, Fig. 1 is a view, partly diagrammatic, showing one form of signaling system embodying my invention. Fig. 2 is a view showing in side 20 elevation, the relay R, shown in Fig. 1. Fig. 3 is a view showing a modified form of signaling system also embodying my invention.

Similar reference characters refer to similar parts in each of the views.

Referring first to Fig. 1, the relay R comprises a thermionic tube *a* containing a filament 2 and a plate or anode 3. The filament 2 is constantly heated to incandescence 25 by a battery 4. The reference character 5 designates a permanent magnet so arranged as to produce a magnetic flux passing through the tube *a* in a path perpendicular to that taken by electric current flowing 30 from the plate 3 to the filament 2. This permanent magnet tends to oppose the flow of current through the tube. The relay also 35 comprises a winding 6 which when energized tends to neutralize the action of the magnet 5 on the flow of current through the 40 tube, and so to permit such current to flow.

The reference characters T and T' designate the track rails of a railway along 45 which traffic normally moves in the direction indicated by the arrow, and which rails are divided by insulated joints 7 to form a track section A-B. A battery 8 is connected across the rails adjacent the exit end of the section, whereas the winding 6 is 50 connected across the rails adjacent the entrance end of the section. Also located adjacent the entrance end of section

A-B is a signal S, which, in the form here shown, is of the semaphore type adapted to indicate "Stop" and "Proceed".

The signal S is provided with a controlling circuit which passes from a battery 9, through the filament 2 and plate 3 of tube *a*, wire 11, operating mechanism of signal S, and wire 12 to battery 9. When current 60 flows in this circuit, the mechanism associated with signal S is operated to cause the signal to indicate proceed, but when the flow of current is arrested the signal moves to the stop position under the influence of 65 gravity or other suitable biasing force.

The operation of the system shown in Fig. 1 is as follows:

When the insulated track section A-B is unoccupied, winding 6 is supplied with current from the track battery 8, and so this winding creates a magnetomotive force which opposes the magnetomotive force of the permanent magnet 5, thereby eliminating or reducing to a small value the magnetic 75 flux in tube *a*. This tube is then conductive, so that current flows in the controlling circuit for signal S, and, consequently, this signal indicates proceed. When a car or train enters section A-B, however, the 80 wheels and axles of such train constitutes a shunt of low resistance around winding 6, so that this winding is substantially de-energized. The magnetomotive force of the permanent magnet 5 being then unopposed 85 then causes magnetic flux to pass through the tube *a*, so that this tube is rendered non-conductive. The consequent de-energization of the controlling circuit for signal S results in this signal moving to the stop position, thus indicating that the section is 90 occupied.

Referring now to Fig. 3, the signal which is here designated S^a, comprises two electric lamps *g* and *r*, adapted when lighted to indicate "Proceed" and "Stop", respectively. The proceed lamp *g* is controlled by a relay R which is similar to the relay shown in Fig. 1, and the stop lamp *r* is controlled by a relay R^a, which is similar to relay R except that the permanent magnet is omitted. The winding 6 for relay R and the winding 6^a for relay R^a are connected in series across the track rails T and T' adjacent the en-

trance end of section A—B, so that these windings are both energized when the section is unoccupied, and de-energized when the section is occupied. The filament 2 in 5 each relay is constantly heated to incandescence by a common battery 4.

The circuit for lamp *g* of signal *S^A* passes from battery 9, through wire 10, filament 2 and plate 3 of relay *R*, wire 11, lamp *g* and 10 wire 12 to battery 9. The circuit for lamp *r* is from battery 9, through wires 10, 13 and 14, filament 2 and plate 3 of relay *R^A*, wire 15, lamp *r* and wire 12 to battery 9.

The operation of the system shown in 15 Fig. 3 is as follows:

When track section A—B is unoccupied, winding 6 is energized so that the magneto-motive force due to the permanent magnet 5 is neutralized which reduces the magnetic 20 flux through the tube to zero or to a small value, with the result that the tube *a* of relay *R* is conductive and so the proceed lamp *g* of signal *S^A* is lighted. Winding 6^a is 25 also energized but it creates a magnetic flux in the tube *a* of relay *R* with the result that this tube is non-conductive and so signal lamp *r* is extinguished. When a car or train enters section A—B, windings 6 and 6^a become de-energized, so that the thermionic 30 tube of relay *R* becomes non-conductive due to the magnetic flux created by the magnet 5, whereas the thermionic tube of relay *R^A* becomes conductive, due to the fact that the 35 supply of magnetic flux to this tube is discontinued. It follows that lamp *g* becomes extinguished and lamp *r* becomes lighted so that signal *S^A* indicates stop.

One important feature of my invention is 40 the provision of a relay having no moving parts. Another important feature is that the track winding 6 or 6^a can be highly insulated from the circuits which it controls; by appropriate design the relay will stand a break down test of several thousand volts 45 between winding 6 or 6^a and the controlling circuits for the signal *S* or *S^A*. Another important feature of the invention is that interruption of the proceed indication circuit of the signal depends solely on the ability of 50 the permanent magnet 5 to maintain its field of flux. Such a magnet when made from properly treated steel is almost as dependable as the force of gravity. Still another important feature is that relay *R*, which 55 controls the proceed indication of the signal in each instance, is a normally open circuit device due, as I have just stated, to the fact that the property of the magnet 5 to maintain its field of flux is dependable to a high 60 degree.

Although I have herein shown and described only two forms of railway signaling system embodying my invention, it is understood that various changes and modifications 65 may be made therein within the scope

of the appended claims without departing from the spirit and scope of my invention.

Having thus described my invention, what I claim is:

1. A railway signaling system comprising 70 a thermionic tube, a circuit including a source of current and said tube, a signal controlled by said circuit, a magnet for opposing the flow of current through said tube, a winding for opposing the effect of said magnet on the flow of current through said tube, and train-controlled means for supplying current to said winding.

2. A railway signaling system comprising 80 a thermionic tube having a plate and a heated filament, a circuit including a source of current and the plate and filament of said tube, a signal controlled by said circuit, a magnet for opposing the flow of current through said tube, a winding for opposing the effect of said magnet on the flow of current through said tube, and train-controlled means for supplying current to said winding.

3. A railway signaling system comprising 90 track rails, a source of current connected therewith, a thermionic tube, a magnet for opposing the flow of current in said tube, a winding receiving energy from said track rails for opposing the effect of said magnet 95 on the flow of current in said tube, a circuit including said tube and a source of current, and a signal controlled by said circuit.

4. A railway signaling system comprising 100 track rails, a source of current connected therewith, a thermionic tube, a magnet for opposing the flow of current in said tube, a winding receiving energy from said track rails for opposing the effect of said magnet 105 on the flow of current in said tube, a circuit including said tube and a source of current, a signal, and means controlled by said circuit when current flows therein for causing said signal to indicate "Proceed".

5. A railway signaling system comprising 110 track rails, a source of current connected therewith, a thermionic tube, a magnet for opposing the flow of current in said tube, a winding receiving energy from said track rails for opposing the effect of said magnet 115 on the flow of current in said tube, a circuit including said tube and a source of current, and a signal comprising an electric lamp included in said circuit.

6. A railway signaling system comprising 120 track rails, a source of current connected therewith, a thermionic tube, a magnet for opposing the flow of current in said tube, a winding receiving energy from said track rails for opposing the effect of said magnet 125 on the flow of current in said tube, a circuit including said tube and a source of current, and traffic governing means controlled by said circuit.

7. A railway signaling system comprising 130

- track rails, a source of current connected therewith, a thermionic tube, a magnet for opposing the flow of current in said tube, a winding receiving energy from said track rails for opposing the effect of said magnet on the flow of current in said tube, a circuit including said tube and a source of current, a second thermionic tube, a winding for said second tube receiving energy from said track rails, a second circuit including said second tube and a source of current, and signaling means controlled by said two circuits.
8. A railway signaling system comprising track rails, a source of current connected therewith, a thermionic tube, a magnet for opposing the flow of current in said tube, a winding receiving energy from said track rails for opposing the effect of said magnet on the flow of current in said tube, a circuit including said tube and a source of current, a second thermionic tube, a winding for said second tube receiving energy from said track rails, a second circuit including said second tube and a source of current, and a signal having a proceed indication lamp included in said first circuit and a stop indication lamp included in said second circuit.
9. A railway signaling system comprising track rails, a source of current connected therewith, a thermionic tube, a magnet for opposing the flow of current in said tube, a winding receiving energy from said track rails for opposing the effect of said magnet on the flow of current in said tube, a circuit including said tube and a source of current, a second thermionic tube, a winding for said second tube receiving energy from said track
- rails, a second circuit including said second tube and a source of current, a signal, and means for causing said signal to give one indication or another according as one of said circuits or the other is energized.
10. A railway signaling system comprising track rails, a source of current connected therewith, a thermionic tube, a magnet for opposing the flow of current in said tube, a winding receiving energy from said track rails for opposing the effect of said magnet on the flow of current in said tube, a circuit including said tube and a source of current, a second thermionic tube, a winding for said second tube receiving energy from said track rails, a second circuit including said second tube and a source of current, and traffic governing means controlled by said two circuits.
11. A railway traffic controlling system comprising a magnetron, a permanent magnet for affecting the electrical conductivity of said magnetron, traffic controlled means for modifying the effect of said magnet on said magnetron, and traffic governing means controlled by said magnetron.
12. A railway traffic controlling system comprising a magnetron, a permanent magnet for affecting the electrical conductivity of said magnetron, a winding for modifying the effect of said magnet on said magnetron, traffic controlled means for varying the effect of said magnet and said winding on said magnetron, and traffic governing means controlled by said magnetron.

In testimony whereof I affix my signature.

SAMUEL M. LUCAS.
